UNITED STATES PATENT OFFICE.

EDWARD N. PORTER, OF BURLINGTON, VERMONT.

DOOR-LATCH.

SPECIFICATION forming part of Letters Patent No. 287,715, dated October 30, 1883.

Application filed June 20, 1883. (Model.)

To all whom it may concern:

Be it known that I, EDWARD N. PORTER, a citizen of the United States of America, residing at Burlington, in the county of Chittenden and State of Vermont, have invented certain new and useful Improvements in Door-Latches; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention is in the nature of improvements in that class of latches specially designed for light frame-work doors—such as screen-doors; and the object of the invention is to improve the construction of the bearing for the latch-lever and the latch-lever locking device.

Before my invention the latch-lever had been supported upon a pivot fixed in lugs on a plate partly covering the upper end of a hand-grasp or handle; and, again, such lever has had its 25 pivotal pin sustained in a recess in the upper end of the handle and backed by an underlying plate next the wood of the door. The lever has been locked on the inside by a hook attached to the inside escutcheon. Now, my 30 invention differs from these things in the following particulars: The bearing for the latch-lever is the outside escutcheon, separate from and independent of the handle, and made in two pieces, which, when put together, constitute an apparently single piece, the lower or 35 inner member having a recess, to permit the passage of the lever down into and through it, and forming a metallic backing for the pivot-pin, and the upper or outer member having a 40 semi-tubular recess and slot for the lever, and its pin and ears to overlap and align with the lower member, the two being united, and the lever thus securely held therein by screws or other fastenings. The inside escutcheon is provided with lugs or projections, to hold the lever-locking hook out of engagement therewith, and said escutcheon is provided with legs and 45 combined with and held in place by an inside handle of peculiar construction; and my inven-

tion herein consists of these details of construction, whereby the appearance, durability, and effectiveness of such latches are improved.

In the accompanying drawings, in the several figures of which like parts are similarly designated, Figure 1 is a perspective view of 55 the parts of a latch containing my improvements in position. Fig. 2 is a vertical section through a door and escutcheon on the near side of the latch-lever. Fig. 3 is a perspective view of the inside escutcheon, and Fig. 4 is a 60 perspective view of the outside escutcheon, dismembered.

The lever *a* is preferably made rectangular, with the handle *b* lowermost, and with a fulcrum pin or shaft, *c*, extending transversely 65 through the same at or near the angle, and having its longer arm *d* provided with a hook, *e*, and terminating beyond said hook in a thumb-piece, *f*. The handle end of this lever overbalances the other arm, thereby making 70 it lock by gravity. The catch for the hook consists of a right-angled casting, *g*, adapted to be secured to the door-jamb, and is provided with a rib or flange, *h*, with which said hook engages automatically, to hold the door 75 shut, and from which said hook is disengaged by depressing the thumb-piece, to permit the opening of the door.

The outside escutcheon, *A*, is composed of a base-plate, *i*, made flat, and provided with 80 a recess, *j*, to receive the lever, and with holes *k* *k*, through which the escutcheon-fastenings pass, and an overlying plate, *l*, provided with a parti-tubular slotted portion, *m*, which covers the recess *j* in plate *i*, and embraces the 85 lever and holds it against lateral and vertical displacement, and in this tubular portion *m* the fulcrum pin or shaft *c* of the lever finds a bearing, the base of which is the flat surface of the plate *i*. The plate *l* is provided with 90 the ears *n* *n*, which overlap the plate *i*, and are provided with holes *o* *o*, aligning with the holes *k* *k* in the plate *i*, thereby providing for the attachment of the two parts of the escutcheon with fastenings common to both. The finish of the two plates *i* *l* is such as to give a 95 general appearance of singleness of the escutcheon, and affords the latch-lever a metal-

lic bearing throughout, and hence such lever does not wear away the door, and is easily applied and removed.

In Fig. 1 the screw *p* is one of the escutcheon-fastenings.

The hole or slot *q* in the door for the passage of the latch-lever is sufficiently large to permit a very large range of movement of said lever within the limits of the inside escutcheon, *r*, for which purpose said inside escutcheon is made with two elongated legs, *s s*, separated by a space of a width slightly in excess of the width of the lever *a*, said legs straddling the lever on the inside of the door, over the hole *q*, and said inside escutcheon being adjustable up and down over said hole, in accordance with the play desired for the lever. This adjustment of the inside escutcheon is effected by changing the point of insertion in the door of its screw *t*.

On the screw *t*, I pivot a hook, *u*, acting by gravity to engage the under side of the latch-lever, to lock said lever with its catch *g*, so as to prevent the opening of the door from the outside.

The door is provided on its inside with a stationary handle, *v*, for convenience in operating the same, and this handle has a foot, *w*, placed over and holding in position the legs of the inside escutcheon. This handle has a sharp toe, *x*, at the end of its foot, to enter the wood of the door, and a screw, *y*, at its heel, to firmly secure it to the door.

The escutcheon *r* has protuberances *r'*, adjacent to the screw *t*, which extend out sufficiently far from the face of the escutcheon to

hold the hook *u* out of engagement with the latch-lever when turned up and away from said lever.

As thus constructed, it is obvious that the latch can be applied equally as well to a right or a left hand door.

What I claim is—

1. The combination, with the latch-lever having the transverse pivot-pin *c*, of the outside escutcheon divided across its face and composed of the flat plate *i*, having the recess *j*, to permit the passage of the latch-lever down into and through it, and the overlying plate *l*, provided with the parti-tubular slotted portion *m*, to receive the pivot-pin of the latch-lever, and with the plate *i*, form a metallic bearing for said pivot-pin, the ears *n n* on plate *l* overlapping the plate *i*, and provided with screw-holes, to align with screw-holes in said plate *i*, as set forth.

2. The combination, with the inside escutcheon having the legs *s*, of the overlying foot *w*, provided with the toe *x* and handle *v*, as shown and described.

3. The combination, with a latch-lever, of the escutcheon *r*, made with protuberances *r'*, to hold the hook *u* on said escutcheon up out of engagement with the latch-lever, as shown and described.

In testimony whereof I do affix my signature in presence of two witnesses.

EDWARD N. PORTER.
